Primary Examiner — Mehri F Bajoul

CLAIM

The ornamental design for a sports target, as shown and described.

DESCRIPTION

FIG. 1 is a perspective view of a sports target showing the claimed design;

FIG. 2 is a front elevation view thereof;

FIG. 3 is a rear elevation view thereof;

FIG. 4 is a left-side elevation view thereof, wherein a right-side elevation view thereof is a mirror image of the left-side elevation view;

FIG. 5 is a top plan view thereof; and,

FIG. 6 is a bottom plan view thereof.

Broken lines in the figures illustrate portions of the sports target that form no part of the claimed design.

1 Claim, 5 Drawing Sheets
